United States Patent Office.

FELIX RODGERS, OF PHILADELPHIA, PENNSYLVANIA.

Design No. 4,018, dated May 10, 1870.

DESIGN FOR A SHADE FOR GAS OR LAMP-BURNERS.

The Schedule referred to in these Letters Patent and making part of the same

I, FELIX RODGERS, of the city of Philadelphia, in the State of Pennsylvania, have invented and produced a new and original Design for a Shade for Gas and Lamp-Burners, of which the following is a specification.

The nature of my said design is fully represented in the accompanying drawing, to which reference is made, and consists of the concave curve *a b*, the straight side *b c*, and the convex curve *c d*, together constituting the exterior form or profile between the top and bottom of the shade.

I do not desire to include the curve *d e*, which forms the profile of the button-flange, as part of my said design.

Claim.

I claim as my invention—
The design for a shade for gas and lamp-burners, substantially as shown and specified.

FELIX RODGERS.
